UNITED STATES PATENT OFFICE.

ROBERT A. CUMMINGS, OF PITTSBURGH, PENNSYLVANIA.

SIFTING OR SCREENING MECHANISM.

1,207,139.

Specification of Letters Patent.

Patented Dec. 5, 1916.

Application filed September 9, 1915. Serial No. 49,745.

To all whom it may concern:

Be it known that I, ROBERT A. CUMMINGS, a resident of Pittsburgh, in the county of Allegheny and State of Pennsylvania, have 5 invented a new and useful Improvement in Sifting or Screening Mechanism, of which the following is a specification.

This invention relates to apparatus for grading or classifying granular or finely divided solid material, such as sand, gravel, clay or the like, and by means of which the material can be very accurately classified or divided into grades of different sizes or other characteristics.

10 The object of the invention is to provide for grading or classifying any granular or finely divided solid material, whether the grains are coarse or of very minute size, or both, and whereby the material is positively 15 separated and accurately divided or classified into uniform grades.

Heretofore the practice has been to grade or classify sand, gravel, clay, and other granular or finely divided material by 20 means of a series of substantially horizontal screens of progressively finer mesh downwardly, and upon the upper one of which the raw, unclassified material is supplied, and which screens are agitated or 25 shaken laterally to cause the finer grades of material to pass through the several screens in succession, each screen throwing off material of a grade corresponding to its openings. In such prior apparatus gravity has 30 been the only force for causing the finer material to pass through the screens and it has been found necessary to agitate the screens 35 constantly and quite violently in order to cause the particles to pass through them,

40 and as the result of such agitation a considerable amount of a finer grade is carried over the edge of each screen along with the coarser grade which it is the purpose of that particular screen to separate out. As a result 45 the separation or classification is not accurate. Furthermore, some materials are so finely divided or the grains are of such minute size that they cannot be separated or classified by ordinary screening methods

50 and must be treated by sedimentation or other settling processes while in suspension in a liquid, so that a mass of coarser material mixed with very finely divided material may require several separate and distinct treatments to separate or classify it into sufficiently distinct classes.

The present invention provides for a progressive separation or classification of any kind of finely divided or granular material, whether containing coarse or very minute grains, or both, into batches or grades of accurately uniform sizes, the grading or classification of the coarse and very fine sizes being effected at the same time in a single apparatus by forcing the material by 60 centrifugal action, either dry or wet, in succession through one or a plurality of screens of increasing fineness of mesh, for grading the coarser sizes; and if grains of very minute size are present, by subjecting this fine 65 material, in suspension in a liquid in an elutriator, to the action of centrifugal force opposed by the flow or travel of a current of liquid carrying the material in suspension, to thereby accurately grade or classify the 70 fine material.

A further object of the invention is to provide apparatus for both screening or shifting the coarser material and grading the more finely divided material in an 80 elutriator so arranged that the elutriator may be dispensed with, whereby the apparatus can be used for screening or sifting dry material or finely divided material in suspension in a liquid without any flow of 85 said liquid and purely by the action of centrifugal force.

A further object of the invention is to provide such a construction of separating 90 chambers or cylinders containing the classifying screens that they may be either filled with liquid or supplied with a current of liquid so as to keep the material in suspension and thereby secure a more rapid operation and prevent clogging of the screens. 95

A further object of the invention is to provide apparatus so constructed that the material being screened or sifted may be given a lateral movement across the screens, as well as a movement directly through said 100 screens, so as to insure all of the finer particles traveling through each of the successive screens and prevent the finer grades being retained along with the coarser grades collected upon any particular screen. 105

Further objects of the invention are in part obvious and in part will appear more in detail hereinafter.

In the drawings, which illustrate a suitable form of mechanism embodying the invention, Figure 1 is a side elevation, partly in section on the line 1—1, Fig. 2, the dotted

lines indicating the elevated position of the cylinder; Fig. 2 is a plan view of the rotatable frame and the parts carried thereby; Fig. 3 is a sectional elevation on the line 3—3, Fig. 1, showing the driving mechanism; Fig. 4 is a detail longitudinal section, on a larger scale, showing one of the separating screens; Fig. 5 is a cross section on the line 5—5, Fig. 1; Fig. 6 is a detail cross section on the line 6—6, Fig. 2; Fig. 7 is a detail view, corresponding to Fig. 1, and showing a different position of the valve member in the elutriator; and Fig. 8 is a detail view, showing a modification.

15 The essential parts of the apparatus illustrated comprise a frame 1 secured to a vertical rotatable shaft 2 and adapted to be whirled around by said shaft, and one or more separating chambers or cylinders 3 mounted in said whirling frame and normally lying in horizontal position, together with suitable means for rotating the shaft 2 in order to whirl the frame 1 and produce a centrifugal action in the separating chambers or cylinders 3.

As illustrated in the drawings, the machine is supported upon a suitable base 4, from which rises an upright frame 5 in which the vertical rotatable shaft 2 is journaled. The machine may be power driven, and for this purpose may be connected to any suitable driving device, such as an electric motor, for example by a belt from said motor passing over a pulley 6 on the driving shaft 2. The particular machine shown may also be operated by hand, and for this purpose is provided with a horizontal shaft 7 journaled at its outer end in a bearing 8 and provided with an operating handle 9. 40 The opposite end of the shaft 7 is journaled in the frame 5 and is provided with a gear 10 meshing with a pinion 11 on a countershaft 12 journaled in a hinged frame 13 which swings about a shaft 14 as an axis, 45 said shaft 14 lying parallel with the shaft 7. On the countershaft 12 is a spiral toothed wheel 15 engaging with a worm 16 on the shaft 2, the latter of which has its upper end squared and fitting a similarly shaped opening in a cross member 17 located at the middle of the frame 1. The hinged frame 13 enables the hand driving mechanism to be thrown out of gear when the machine is operated by power, and to hold the hand driving mechanism in gear the frame 13 is provided with a depending arm 18 lying opposite an opening in the frame 5 in which is an adjustable pressure screw 19 which can be forced into engagement with the arm 18 to press the gears 11 and 15 into coöperating engagement with their companion gears 10 and 16.

By means of either the power driving pulley 6 or the hand driving mechanism described the vertical shaft 2 can be rotated at

high speed and the frame 1 carried by said shaft is rapidly whirled around so as to produce the centrifugal action in the separating devices, as will more fully herein-after appear.

Two or more separating chambers may be utilized, located on opposite sides of the axis of the shaft 2, but in the drawings a single separating chamber is shown, which is preferably of cylindrical form and is mounted 75 on the frame 1 with its axis horizontal and longitudinal of said frame. The chamber is divided interiorly by a series of screens preferably arranged transversely to its axis, so that the material supplied to the separating 80 cylinder will be forced by centrifugal action through the screens from the end of the separating chamber located nearest the shaft 2 to its opposite end.

The separating chambers may be variously constructed, but preferably will be so arranged that the material to be classified can not escape therefrom without passing through the screens, and preferably also in such a manner that a constantly flowing 90 stream of liquid may be passed through said screens in order to assist the classifying operation and to produce a further grading or classifying operation in the elutriator, as will more fully appear.

As specifically shown in Fig. 1, the separating cylinder is provided with a series of transverse screens 20 which are successively of finer mesh from the inner to the outer end of the chamber, and which screens have 100 their edges clamped between annular members 21 and 22 threaded to each other. The annular member 22 on each screen nests within the annular member 21 of the next adjacent screen, so that the series of annular 105 members for the several screens form practically a continuous cylindrical shell. The outermost ring 22 nests within a plain ring 23 abutting a funnel-shaped pan 24, forming the outer end of the separating chamber, 110 and the innermost of the annular members 21 has fitted thereagainst a cap 25, said cap and the pan 24 being connected by a cylindrical sheet metal drum or casing 26, whose inner surface closely fits a series of outwardly extending projections 28 on the annular members 21 and 22 for spacing the screens centrally in their casing. One of 115 said rings, such as the ring 23, may be provided with a small hole or holes 23^a permitting the liquid to flow in between the rings and their casing 26 to prevent leakage, if desired.

The material to be graded or classified is placed in the chamber 30 between the cap 125 member 25 and the first screen 20, and after the classification by forcing the material by centrifugal action through the several screens in series, the coarsest grade of material will remain in said chamber 30 while 130

the material in the chambers between successive screens will be of successively finer and finer grades, with the finest material in the chamber 31 between the last of the 5 screens and the outer pan 24. The material may be screened in dry condition, or if desired, the entire separating cylinder may be filled with liquid, such as water, in which the material is held in suspension so that it 10 more readily passes through the successive screens. The fine material collected in the chamber 31 may be subjected to a further grading or classifying operation so as to separate it into other grades. For this purpose 15 an elutriator is attached to the outer end of the chamber 3 and so arranged that communication between the chamber 3 and the elutriator may be either closed to dispense with the elutriator in classifying dry 20 material or when said elutriator, for other reasons, is not required, or may be established so that both classifying devices operate simultaneously.

The elutriator comprises an inner member 25 32 whose inner end is threaded upon the outer end of the pan 24 and is provided with several outwardly extending radial wings or projections 33, and whose outer portion is provided with a plurality, three 30 being shown, of annular concentric walls 34 which lie within the annular chambers or spaces 35 between the annular concentric walls 36 of an outer member 37. The walls 34 and 36 form a tortuous passage through 35 the elutriator, conducting the liquid and the material held in suspension therein successively through the three chambers 35. The walls are so proportioned in thickness and relative spacing that the several chambers 40 35 in turn are of increasing cross sectional area, so that the stream of liquid flowing therethrough has a gradually decreasing velocity, as will be readily understood. The outer member 37 of the elutriator is threaded 45 into a cap 38 whose inner reduced end is connected to the outer end of a shell or casing 39 surrounding the cylinder 3, and of larger size than said cylinder so as to form 50 an annular passage 40 between the outer shell and cylinder 3. The wings or projections 33 on the inner member 32 of the elutriator fit within the inner wall of the cap 38 and hold the cylinder 3 and inner member of the elutriator in central position 55 in the outer shell or casing. The cylinder 3 is also held securely against longitudinal movement in the casing 39 by clamp screws 39a, which also force the caps and rings of the inner shell 3 into close interlocking or 60 nesting engagement with each other.

The inner end of the chamber 30 within the cap 25 communicates with a passage 41 in a member 42 attached to the cross member 17 of the frame 1, said passage at its 65 opposite end communicating with a vertical

pipe 43 whose axis coincides with the axis of the shaft 2 around which the frame 1 revolves. This enables the material in suspension in a liquid, or clear liquid, to be introduced to the chamber 3 through a substantially stationary conduit, which may be easily connected to a supply conduit by a swivel joint. The annular passage 40 between the inner and outer casings communicates at its inner end with an annular passage 44 in the member 42, which passage in turn communicates with an upwardly extending pipe or conduit 45 whose upper end has a lateral extension or bend 46 lying within a container or receptacle 47 carried by and rotatable with the pipe 43, said receptacle being open at its upper end, as at 48, and having a downwardly extending discharge pipe 49 whose lower end travels around in a stationary receiver 50 carried by the frame 5, said receiver having a suitable discharge pipe 51. With this arrangement the dry material may be placed in the chamber 30 and subjected to the action of a current of liquid introduced through the pipe 43, or the material may be mixed with the liquid in a suitable lixiviator, and introduced directly into the apparatus in suspension in a current of liquid. The stream of liquid passes through the separating chamber 3, forcing the material in turn through the successive separating screens 20, each of which collects a particular grade of a size which will not pass through said screen. The finer material passes to the chamber 31 and thence into and through the tortuous passages of the elutriator. On the inner side of each of the walls 34 is a passage 52 through which the material and liquid pass outwardly, so that the flow is assisted by centrifugal force. On the outer side of each of said walls is a passage 53, and in said passages the liquid and material travel inwardly. In these passages the flow of the material with the current is opposed by centrifugal force, which tends to throw the particles of material outwardly. This produces the well known grading action which separates the material into grades of decreasing size, the coarser grade being deposited or collected in the inner chamber 35 and the finer grades successively in the outer chambers. The clear liquid remaining after the last separation in the outer chamber 35 travels inwardly through the annular passage 40, then through the passage 44 and through pipe 45 into the receptacle 47, from which it passes downwardly through the pipe 49 to the outlet from the receiver 50.

The grades of material deposited in the several chambers 35 depend in size upon the velocity of flow of the liquid passing through said chambers, since each chamber collects material of such a size or weight that the centrifugal force tending to throw

such material outwardly is greater than the force of the current tending to carry the material inwardly. The pipe 45 leading into the receptacle 47 is rotatable in its supports about its own axis, so that the outlet from said pipe through the lateral bend 46 can be placed at different distances from the axis of the shaft 2, as indicated by the dotted lines in Fig. 2. The velocity of flow 10 of the stream of liquid through the entire apparatus depends upon the distance of the outlet from this pipe 45 from the axis of the shaft 2, which distance determines the head produced by centrifugal force. Consequently, by adjusting said pipe to different 15 positions the velocity of flow of the liquid through the entire apparatus can be varied so as to vary the grades deposited in the various chambers 35. Each chamber 35 is 20 provided at its outer end with an outlet through which the material deposited therein may be removed. As shown, the outer member 37 of the elutriator is provided with an opening into each of said chambers, said 25 openings being closed by tapered pins 54 held in place by winged nuts 55.

For closing communication between the separating chamber 3 and elutriator the inner end of the member 32 is provided with 30 a valve seat 56 for coöperation with a valve member 57 carried on the inner end of a tube 58 threaded into the outer end of the member 37. In its outer position, as shown 35 in Fig. 1, when the chamber 3 and elutriator are in communication with each other, the valve member 57 is seated against the inner end of the inner annular wall 36 of the outer member 37, but by screwing the tube 58 inwardly to the position shown in Fig. 7, 40 communication between the chamber 3 and elutriator is wholly shut off. Within the tube 58 is a solid rod 59 whose outer end is threaded into a guide 60 and is provided 45 with a longitudinal passage 61 opening at one end through the outer end of the rod and at its inner end communicating through a port 62 with an annular space 63 between the rod 59 and tube 58. The inner end of 50 said rod works in an opening through the valve member 57 and is provided with a head 64 normally sealing said opening and with a longitudinal slot 65 behind said head. This rod normally occupies the position 55 shown in Fig. 1, so that the opening through the valve 57 is closed by the head 64, and no material can pass outwardly through said valve. The rod may be adjusted inwardly, however, to the position shown in Fig. 7, in 60 which position material collected in the chamber 31 may pass outwardly through the slot 65 to the passage 63 and thence outwardly through port 62 and passage 61. This device is used for cleaning the apparatus or for removing a grade collected or 65 deposited in the chamber 31.

The outer end of the casing 39 is journaled in a ring 66 provided with two outwardly extending trunnions 67 engaging in openings in the side members of the frame 1, so that the chamber or cylinder 3 and the 70 elutriator can be tilted upwardly to the position shown in dotted lines, Fig. 1, in order to introduce a new charge of material to the chamber 3, or to remove the several screens from said chamber so as to take out the 75 grades deposited therein. Inasmuch as the centrifugal force produces a severe outward thrust of the chamber 3 and elutriator, suitable antifriction means is provided for the bearing in the ring 66, such as the ballbearings shown at 68. Ballbearings are also provided at the inner end of the chamber 3, the outer member 70 of said bearing being threaded internally to receive a longitudinally adjustable ring 71 carried by the member 42. This member 71 can be disconnected from the member 70, by screwing it to the 80 position shown in dotted lines, Fig. 1, which disconnects the chamber 3 from the member 42 and enables it to be lifted to the 85 position shown in dotted lines for inserting a new charge.

When two separating chambers or cylinders are used both thereof will communicate with the same feed pipe 43, and said chambers or cylinders will be mounted on opposite sides of the axis of rotation of the shaft 2, so that they balance each other. In the drawings, only a single cylinder is shown, said cylinder being counterbalanced by a 90 suitable counterweight 75, which is clamped between the two nuts 76 adjustable longitudinally upon a threaded shaft 77 carried by cross members 78 of the frame 1. This counterweight can be adjusted on its supporting shaft in order to accurately counterbalance the separating cylinder.

In addition to the whirling motion to which the separating cylinder is subjected, said cylinder is also preferably given a rotary motion about its own axis, so as to 100 change the position of the screens relatively to the material passing therethrough and produce a centrifugal action on said material radial to the axis of the cylinder 3, to 105 assist in forcing the material through the screens. This rotary movement can be effected by various means and may be either an intermittent or a continuous rotary movement. As shown in Fig. 1, a suitable abutment 80 is secured to the frame 5 with its upper end in position to be contacted by the periphery of the cylinder 39 as it moves over the same. This abutment can be made of some friction material, such as leather or 110 the like to coöperate with the smooth surface of the cylinder 39, and produces a gentle but regular intermittent rotation of the cylinder. Various other means may be 115 applied for giving said rotary motion, such 120 as a gear or the like.

as providing the periphery of the cylinder with ratchet notches or teeth and substituting a pawl for the abutment member 80. If a continuous rotary movement is desired the 5 cylinder may be provided with gear teeth 81, as shown in Fig. 8, which mesh with a horizontal annular rack 82 mounted on the frame 5 concentric with the shaft 2, or, some of the teeth of the rack 82 may be omitted 10 at intervals, so as to produce an intermittent rotation of the cylinder.

Whenever the cylinder is rotated upon its axis the material being forced through the screens is gently shifted laterally across the 15 screens and clogging of the screens is prevented and a more ready passage of the material through the screens is effected. The separating cylinder may also be moved or vibrated transversely about its axis to assist 20 in distributing or moving the particles transversely of the separating screens. One suitable construction for producing this result consists in providing one or a plurality of small knobs or cams 83 upon the frame 5 just below the lower end of the member 17, which is slideable vertically upon the upper squared end of the shaft 2 and is provided 25 with a depending projection 84 which travels over and engages successively the knobs 30 83, each engagement producing a slight lift of the frame 1 and all of the parts carried thereby. The result is a jarring or vibration of the separating cylinder which is of material assistance in securing the passage of the 35 particles through the screens. This device may be used alone or in combination with suitable means such as that described for rotating the receptacle about its own axis.

In the apparatus described the material 40 does not escape from the edges of the screens and by the action of centrifugal force the finer particles are forced through the several screens in succession. Each screen holds back only such particles as are too 45 large to pass through it, and the positive action of the centrifugal force insures that all particles of a smaller size will be passed through that particular screen. Consequently the material is separated or classified 50 into grades of uniform size, and there is no danger of a coarser grade containing a portion of the finer material, as with existing screening methods. The result is that the 55 classification is much more accurate and sharply defined than in existing methods. When the material to be classified contains particles of very minute size, such particles can be further accurately graded or classified 60 in the elutriator by the action of a current or stream of liquid opposed by centrifugal force. The centrifugal force acts to force the particles very rapidly through the elutriator, as a result of which a batch of unclassified material can be separated very 65 rapidly into definite grades.

What I claim is:

1. Apparatus for classifying solid materials comprising a rotatably mounted frame, a receptacle mounted on said frame, and an inner shell in said receptacle containing a 70 plurality of screens of varying mesh whose planes are parallel to the axis of rotation of said frame.

2. Apparatus for classifying solid materials comprising a rotatably mounted frame, 75 a receptacle mounted on said frame, and a plurality of screen members so mounted in said frame as to form an inner shell therein with a passage surrounding said members.

3. Apparatus for classifying solid materials comprising a rotatably mounted frame, a receptacle mounted on said frame, and a plurality of screens of varying mesh having interlocking peripheral portions forming an inner shell in said receptacle and spaced 80 from said receptacle to form a passage surrounding said screens.

4. Apparatus for classifying solid materials comprising a rotatably mounted frame, a receptacle mounted thereon, a removable 90 cap on said receptacle, and a plurality of screens of varying mesh having interlocking peripheral portions held together by said cap to form an inner shell in said receptacle.

5. Apparatus for classifying solid materials comprising a rotatably mounted frame, a receptacle mounted thereon, a removable cap on said receptacle, and a plurality of screens in said receptacle with their planes parallel to the axis of rotation of said frame, the screen nearest said cap being of the coarsest mesh and each succeeding screen being of finer mesh than the preceding screen. 95

6. Apparatus for classifying solid materials comprising a rotatably mounted frame, a receptacle mounted thereon, a removable cap on said receptacle, a plurality of screens in said receptacle with their planes parallel to the axis of rotation of said frame, the screen nearest said cap being of the coarsest mesh and each succeeding screen in order being of finer mesh than the preceding screen, interlocking peripheral portions on said screens, and means for forcing said 105 portions into mutual interlocking engagement. 110

7. Apparatus for classifying solid materials comprising a rotatably mounted frame, a receptacle journaled on said frame, an inner shell containing a plurality of screens of varying mesh in said receptacle, means for rotating said frame, and means for rotating said receptacle relatively thereto. 120

8. Apparatus for classifying solid materials comprising a rotatably mounted frame, a receptacle journaled on said frame, a plurality of screen members so mounted in said frame as to form an inner 130

- shell therein, means for rotating said frame, and means for rotating said receptacle relatively thereto.
9. Apparatus for classifying solid materials comprising a rotatably mounted frame, a receptacle journaled in said frame, a plurality of screens of varying mesh having interlocking peripheral portions forming an inner shell in said receptacle, means for rotating said frame, and means for rotating said receptacle relatively thereto.
10. Apparatus for classifying solid materials comprising a rotatably mounted frame, a receptacle journaled therein, a removable cap on said receptacle, a plurality of screens of varying mesh having interlocking peripheral portions held together by said cap to form an inner shell in said receptacle, means for rotating said frame, and means for rotating said receptacle relatively thereto.
11. Apparatus for classifying solid materials comprising a rotatably mounted frame, a receptacle journaled therein, a removable cap on said receptacle, a plurality of screens in said receptacle, the screen nearest said cap being of the coarsest mesh and each succeeding screen in order being of finer mesh than the preceding screen, means for rotating said frame, and means for rotating said receptacle relatively thereto.
12. Apparatus for classifying solid materials comprising a rotatably mounted frame, a receptacle journaled therein, a removable cap on said receptacle, a plurality of screens in said receptacle, the screen nearest said cap being of the coarsest mesh and each succeeding screen being of finer mesh than the preceding screen, interlocking peripheral portions on said screens, means for forcing said portions into mutual interlocking engagement, means for rotating said frame, and means for rotating said receptacle relatively thereto.
13. Apparatus for classifying solid materials comprising a rotatably mounted frame, a receptacle journaled on said frame, an inner shell containing a plurality of screens of varying mesh in said receptacle, means for rotating said frame, and means for rotating said receptacle relatively thereto and for jarring the same.
14. Apparatus for classifying solid materials comprising a rotatably mounted frame, a receptacle journaled on said frame, a plurality of screen members so mounted in said frame as to form an inner shell therein, means for rotating said frame, and means for rotating said receptacle relatively thereto and for jarring the same.
15. Apparatus for classifying solid materials comprising a rotatably mounted frame, a receptacle journaled in said frame,
- a plurality of screens of varying mesh having interlocking peripheral portions forming an inner shell in said receptacle, means for rotating said frame, and means for rotating said receptacle relatively thereto and for jarring the same.
16. Apparatus for classifying solid materials comprising a rotatably mounted frame, a receptacle journaled therein, a removable cap on said receptacle, a plurality of screens of varying mesh having interlocking peripheral portions held together by said cap to form an inner shell in said receptacle, means for rotating said frame, and means for rotating said receptacle relatively thereto and for jarring the same.
17. Apparatus for classifying solid materials comprising a rotatably mounted frame, a receptacle journaled therein, a removable cap on said receptacle, a plurality of screens in said receptacle, the screen nearest said cap being of the coarsest mesh and each succeeding screen in order being of finer mesh than the preceding screen, means for rotating said frame, and means for rotating said receptacle relatively thereto and for jarring the same.
18. Apparatus for classifying solid materials comprising a rotatably mounted receptacle, a screen within said receptacle having its surface in a plane parallel to the axis of rotation, and means for conducting liquid through said screen.
19. Apparatus for classifying solid materials, comprising a rotatably mounted receptacle, a plurality of screens of varying mesh therein and having their surfaces in planes parallel to the axis of rotation, and means for conducting liquid successively through said screens.
20. Apparatus for classifying solid materials, comprising a rotatably mounted frame, a receptacle thereon containing a plurality of screens of varying mesh with their surfaces in planes parallel to the axis of rotation, and means for circulating liquid through said screens.
21. Apparatus for classifying solid materials, comprising a rotatably mounted frame, a receptacle journaled on said frame, a plurality of screens of varying mesh in said receptacle whose surfaces are in planes parallel to the axis of rotation, and means for circulating liquid successively through said screens.
22. Apparatus for classifying solid materials, comprising a rotatably mounted frame, a receptacle on said frame, an inner shell containing a plurality of screens of varying mesh in said receptacle, and a casting surrounding said receptacle and forming a passage communicating with the space within said receptacle.
23. Apparatus for classifying solid mate-

rials, comprising a rotatably mounted frame, a receptacle on said frame, an inner shell containing a plurality of screens of varying mesh in said receptacle, a casing 5 surrounding said receptacle and forming a passage communicating with the space within said receptacle, and means for supplying a stream of liquid to said receptacle.

24. Apparatus for classifying solid materials, comprising a rotatably mounted frame, a receptacle journaled on said frame, an inner shell containing a plurality of screens of varying mesh in said receptacle, and a casing surrounding said receptacle 10 and forming a passage communicating with the space within said receptacle.

25. Apparatus for classifying solid materials, comprising a rotatably mounted frame, a receptacle journaled on said frame, 20 an inner shell containing a plurality of screens of varying mesh in said receptacle, a casing surrounding said receptacle and forming a passage communicating with the space within said receptacle, and means for 25 rotating said receptacle.

26. Apparatus for classifying solid materials, comprising a rotatably mounted frame, a receptacle containing a screen pivotally mounted in said frame, and means 30 for conducting liquid through said receptacle.

27. Apparatus for classifying solid materials, comprising a rotatably mounted frame, a receptacle pivotally mounted in 35 said frame on an axis transverse to the axis of rotation of said frame and containing a screen, said receptacle being also rotatable about an axis perpendicular to said first named axes, and means for conducting liquid 40 through said receptacle.

28. Apparatus for classifying solid materials, comprising a rotatably mounted frame, a receptacle pivotally mounted in said frame on an axis transverse to the axis 45 of rotation of said frame and containing a screen, said receptacle being also rotatable about an axis perpendicular to said first named axes, means for conducting liquid through said receptacle, and means for rotating said receptacle in its frame.

29. Apparatus for classifying solid materials, comprising a frame, a receptacle therein containing a screen and communicating with a series of chambers of different 55 areas of cross section, and means for conducting liquid through said screen and chambers.

30. Apparatus for classifying solid materials, comprising a receptacle containing a 60 screen, an elutriator communicating with said receptacle, and means for closing com-

munication between said receptacle and elutriator.

31. Apparatus for classifying solid materials, comprising a rotatably mounted frame, a receptacle journaled therein and containing a screen, an elutriator communicating with said receptacle, and means for conducting liquid through said receptacle and elutriator. 65 70

32. Apparatus for classifying solid materials, comprising a rotatably mounted frame, a receptacle carried by said frame and containing a plurality of screens of varying mesh, a casing surrounding said receptacle and forming a passage therebetween, and an elutriator connected to said casing and communicating with said passage and with the space within said receptacle. 75

33. Apparatus for classifying solid materials, comprising a rotatably mounted frame, a receptacle carried by said frame and containing a plurality of screens of varying mesh, a casing surrounding said receptacle and forming a passage therebetween, an elutriator connected to said casing and communicating with said passage and with the space within said receptacle, and means for closing communication between said receptacle and elutriator. 80 85 90

34. Apparatus for classifying solid materials comprising a rotatably mounted frame, a receptacle mounted on said frame at one side of the axis of rotation and adapted to be whirled around by the same, 95 and a plurality of screens of varying mesh mounted in said receptacle with their planes parallel to the axis of rotation of said frame.

35. Apparatus for classifying solid materials comprising a rotatably mounted frame, a receptacle journaled on said frame and containing a plurality of screens of varying mesh with their planes parallel to the axis of rotation of said frame, means for rotating said frame, and means for rotating 100 105 said receptacle in said frame.

36. Apparatus for classifying solid materials, comprising a rotatably mounted frame, a receptacle journaled on said frame, a plurality of screens mounted in said frame 110 with their planes parallel to the axis of rotation of said frame, means for rotating said frame, means for rotating said receptacle in said frame, and means for jarring said receptacle. 115

In testimony whereof, I have hereunto set my hand.

ROBERT A. CUMMINGS.
